(57) **CLAIM**

The ornamental design for a container for volatilizing chemicals, as shown and described.

DESCRIPTION

FIG. 1 is a perspective view of a container for volatilizing chemicals showing our new design;

FIG. 2 is a front view thereof; the rear view being a mirror image thereof;

FIG. 3 is a left side view thereof; the right side view being a mirror image thereof;

FIG. 4 is a top plan view thereof;

FIG. 5 is a bottom plan view thereof; and,

FIG. 6 is a referential front view thereof indicating transparent part.

The portions of the article in broken lines are shown for illustrative purposes only and form no part of the claimed design.

1 Claim, 6 Drawing Sheets

FIG. 1

FIG. 2

FIG. 3

FIG. 4

FIG. 5

FIG. 6
